UNITED STATES PATENT OFFICE.

JOSEPH VICTOR STOLPER, OF CHICAGO, ILLINOIS.

GAME.

Application filed October 14, 1922. Serial No. 594,595.

To all whom it may concern:

Be it known that I, JOSEPH VICTOR STOLPER, a citizen of the United States, and a resident of Chicago, in the county of Cook and State of Illinois, have invented a new and useful Improvement in Games, of which the following is a full, clear, and exact description.

My invention relates to improvements in games, and it consists in the combinations, constructions, and arrangements herein described and claimed.

An object of my invention is to provide a game of the character described by means of which any ordinary card game requiring five cards to a hand, such as poker, may be played.

A further object of my invention is to provide a game of the character described in which a plurality of rotatably mounted discs are used, each of the discs having legends imprinted thereon, the legends consisting of sets of four of a like character, and so arranged that no two legends of the same character are on the same disc. It is apparent therefore that four legends of like character may be disclosed at one time, provided the discs are in the proper position, thus making what is known in card games as four of a kind.

A further object of my invention is to provide a game of the character described by means of which card games may be played and in which the shuffling of the cards by each player is entirely obviated.

A further object of my invention is to provide a game of the character described that is compact in form and in which there are no loose parts which might become lost in handling or transporting the game.

Other objects and advantages will appear in the following specification, and the novel features of the invention will be particularly pointed out in the appended claim.

My invention is illustrated in the accompanying drawings, forming part of this application, in which—

Figure 1 is a front elevation of an embodiment of my invention, a portion broken away, and

Figure 2 is a sectional view along the line 2—2 of Figure 1.

In carrying out my invention, I make use of a casing 1 having a front panel 2 which is secured to the casing after the interior mechanism of the game has been inserted.

Th panel 2 is secured to the casing 1 by means of a celluloid cement where the casing and panel are made of celluloid. Ordinarily, I prefer to construct the casing and panel of white celluloid. The ends of the casing are curved as shown at 3, which obviates the presence of sharp corners that might mutilate the pocket of a wearer when the game is carried about.

The interior mechanism of the game comprises a metal sheet 4 which closely fits the casing and which rests against the inner wall 5 of the rear wall 6 of the casing. The sheet 4 is provided with three raised portions or bosses 7 that are formed in the sheet by drawing the metal in a manner well known in the art. Each of these bosses is provided with an opening 8 therethrough, in which a rivet 9 is set, the body portion of the rivet being arranged to extend toward the panel 2. Two additional openings 10 are punched through the sheet 4 midway between the bosses 7 and on a line with the openings 8. Rivets 11 are set in the openings 10 and likewise extend toward the panel 2.

A disc 12 of celluloid having an opening 13 centrally located therein, is rotatably mounted upon each of the rivets 9 and 11. The diameters of the discs 12 are such that a portion of the disc protrudes above the upper wall 14 of the casing 1 and the panel 2. The panel 2 is provided with an arcuate recess 15 in its upper wall for each of the discs 12. This recess 15 is of a sufficient breadth to permit slightly less than one quarter of the disc to be visible therethrough.

Each of the discs 12 is divided into eight sectors and each of the sectors is marked with a legend designating one of forty cards of a deck of ordinary playing cards. I choose to eliminate the cards from deuces to fours, inclusive, and use the higher cards 100 on the discs. The legends on the discs 12 are arranged so that there are never more than four aces, four kings, four eights, etc., visible through the recesses 15 as the discs are rotated.

Means for preventing the sheet 4 from moving toward the panel 2 is provided in rivets 16 which pass through the sheet 4 and the rear wall 6 of the casing 1.

From the foregoing description of the various parts of the device, the operation thereof may be readily understood. In op-

eration of my game, each of the players is provided with one of the devices, and at a given signal, each player quickly runs the index finger or the palm of the hand along 5 the upper wall 14 of the casing 1' of the panel 2. This movement will set each of the discs 12 into rapid rotation. The device is then held in the hand until the discs come to a stand-still. When the discs have 10 ceased in their movement, one of the eight legends on each of the discs will be visible through the recess 15. The visible legends will indicate the value of the hand, such as a straight, four of a kind, or any other well 15 known combination of cards.

The players, then make what necessary bids there are, or place what chips are required on the table, in accordance with the rules of the game, and the game may proceed 20 in precisely the same manner as though cards were used in place of a mechanical device.

One of the important advantages of my invention is that a miss-deal, that is, one card 25 too many or one card short, is absolutely

impossible. The deal or the equivalent to the deal is always exact, since the recesses 15 are of such dimension that only one entire sector of the disc may be seen at one time. It is true that a portion of each of the sectors may show through the recess 15, but that one which shows the greatest area is taken, for the sector, the legend on which is to count.

I claim:

A game of the character described; comprising a casing open at the top, five discs rotatably mounted in said casing and arranged so that a portion of each disc projects through the opening at the top of said casing, each of said discs being marked off, into equal sectors and each sector of said discs having a legend imprinted thereon, the legends consisting of sets of four of like character, there being no two of the same character on any one disc, said casing having portions of its outer wall cut away, whereby one legend on each of said discs may be visible at a time.

JOSEPH VICTOR STOLPER.
